UNITED STATES PATENT OFFICE.

ERWIN A. GEIGER, OF RIDGEWOOD, NEW JERSEY; AUGUST F. SCHRAEGLE, OF RIDGEWOOD, AND HENRY T. JENNINGS, OF GLENDALE, NEW YORK, ASSIGNORS TO RAPID ADDRESSING MACHINE COMPANY, A CORPORATION OF NEW YORK.

SELECTIVE ATTACHMENT FOR ADDRESSING MACHINES.

Application filed June 8, 1926. Serial No. 114,415.

The invention relates to addressing machines in general, and more particularly to that type in which a series of stencil cards form a part of the printing mechanism. It is here illustrated as it would be applied to an addressing machine of the general construction shown in Patent No. 1,256,509 granted to E. D. Belknap Feb. 19, 1918, which has a printing mechanism and a card feeding mechanism both under control of the operator for printing from any one stencil card and discharging it, or for discharging it without printing from it, or for holding it in printing position while several printing operations are performed with it.

The object of the present invention is to automatically stop the machine when a card having certain classification features arrives in printing position although the operator continues to hold down a pedal which normally causes the machine to run on, and to do this whether the cards of all other classes are being used for printing, or are being fed through without printing from them. As described in the above noted Patent No. 1,256,509, machines of the type to which our invention is here shown as applied normally, operate through only one cycle and then automatically stop, unless the operator holds down a pedal which leaves the driving clutch in gear. There are three such pedals in machines of this type. Pressing down any one of these will start the machine, but, on its release causes the machine to stop at the end of the current cycle. One pedal, when down, starts the machine printing from all cards fed from the magazine. A second pedal, when pressed down, causes the machine to skip all cards, and a third pedal (in the machine as marketed), while held down, causes the machine to "repeat" or print a series of impressions with one stencil card.

In our Patent No. 1,518,912, granted Dec. 9, 1924, we have described a selective attachment for the machine of the prior Belknap patent, above referred to, by which attachment such machine may be set so as to run continuously (instead of stopping at the end of each cycle unless positively controlled by the operator to continue) but will be automatically stopped whenever a card of a special class reaches printing position, thus enabling the operator to then resume

control of the machine and either skip or print from that particular card, also thereby at the same time resetting the machine so that it will again go on printing or skipping all cards until another specimen of the selected class again trips the mechanism and automatically stops the machine for a re-exercise of the operator's power of choice as to what is to be done with the card then occupying the printing position.

The object of our present invention, which may be called a specific modification or improvement on the broad idea disclosed in our above mentioned patent, is to produce this automatic action, which will stop the machine, while the operator is holding down either the printing or skipping pedal to produce the desired usual operation of the machine,—as contra-distinguished from our prior specific embodiment of an automatic trip attachment by which the pedal is locked down to keep the machine running, and that lock is tripped by the selective mechanism to permit the pedal to rise and thereby stop the machine, all in the manner described in the Belknap patent; both forms of our broad invention being primarily designed as attachments to the original machine of the Belknap patent, but being capable of application to other machines of the same general type.

To accomplish this above described result we employ detachable connections from the printing pedal and from the skipping pedal to the clutch throw-out mechanism, and enable the selective mechanism (when actuated by a card of the selected class) to break whichever such connection is under its control at the time. Consequently the clutch then throws out and the machine stops at the end of the current cycle, although the operator is still holding down one of the pedals that normally cause it to run on, and the operator must thereafter re-establish the thus broken connection to the clutch throw-out before he can again start the machine by again pressing down that particular pedal which is under selective control. Our present invention also embodies certain other specific features of operation and advantage which will be hereinafter pointed out in detail.

The best form of apparatus at present

known to us embodying our invention is illustrated in the accompanying seven sheets of drawings in which,

Fig. 1 is a side elevation of one form of machine to which the invention has been applied.

Fig. 1^a is a similar side elevation but on a larger scale and with parts broken away.

Fig. 1^b is an enlarged detail front view of 10 the throw-out clutch with parts broken away.

Fig. 2 is a plan view, parts being broken away and others shown in section.

Fig. 3 is a detail plan view on a still larger scale showing the selector fingers and 15 connected parts.

Fig. 4 is an end elevation of the portion 20 of the mechanism illustrated in plan in Fig. 3, with parts shown in section, or broken away, and with the electric circuit in dia-

gram.

Fig. 5 is a detail section on a vertical plane indicated by line 5—5 of Fig. 2 with parts broken away.

Fig. 6 is a perspective detail view of the 25 trip mechanism.

Fig. 7 is an enlarged detail of one of the 30 pedal disconnecting devices forming part of said trip mechanism.

Fig. 8 is a plan view of the three pedals 35 and trip mechanism, with certain connecting parts and parts of the main frame shown in section, and with others broken away.

Fig. 9 is a detail of the "repeat" mechanism 40 and an attachment thereto for disabling the trip mechanism, parts being broken away and others shown in section.

Fig. 10 is an enlarged vertical section taken on line 10—10 of Fig. 9.

Fig. 11 shows the preferred form of 45 stencil card which forms an element of the printing and selecting mechanism, and

Fig. 12 is a detail cross section on line 12—12 of Fig. 11.

Throughout the drawings like reference 50 characters indicate like parts. The general structure and mode of operation of the addressing machine which is of standard form made under the above mentioned Belknap patent will first be described in part and then the structure of the attachment thereto, constituting the present invention, will be explained, together with the manner in which it automatically controls the operation 55 of the said machine.

A is a magazine of address bearing stencil cards which are fed to an inking and impression mechanism, generally represented by B, along grooved card guides 36, extending from the bottom of magazine A, through mechanism B, to a receiving magazine C. The general structure of the machine comprises the uprights 1, 1, cross bars 3, 23 and table 2. Motive power is transmitted from 60 electric motor 4, through belt 5 to grooved

pulley 6, journaled on stud shaft 7. This pulley is thereby rotated in a counter-clockwise direction (looking at Fig. 1 and, through a clutch 10 (shown in detail in Fig. 1^b) rotates main crank 70 (Figs. 1 and 1^b). 70 This crank, through connecting rod 30, bell crank 31, (pivoted at 32) and link 73, reciprocates card feeding claws 74, which, on their forward travel to the right hand (Figs. 1^a and 10), feed out the bottom card 75 43 from magazine A along guides 36, toward inking and impression mechanism B. Said crank 70, through connecting rod 71, also reciprocates T-cam 46, which operates said inking and impression mechanism. 80 This cam 46, pivoted on shaft 45 which is held in housing 48, has a cam slot 66 which engages roller 65 mounted on arm 64, of a lever 62—64, pivoted at 63 in housing 67, the other arm 62 of which lever is pivoted to 85 yoke 60, which operates an inking roller (not shown) along the under side of card 43^b (Fig. 2) which is in printing position. No printing operation results, however, unless an article (such as an envelope, wrapper 90 or catalogue) has been first placed by the operator over said card 43^b and the platen head 55 has been swung down upon it.

T-cam 46 also operates said platen head 55, unless the operating mechanism therefor 95 has been disabled, as will be now described. Platen 55, pivoted on the main frame at 54, is normally held up in the position shown in Fig. 1 by spring 56. On the depending arm 53 of said platen, however, lever 51 carrying roller 50 is pivoted at 52 and is normally held down in operative position by spring 57, so that said roller 50 then engages the external face 49, 47 on said T-cam 100 46. Consequently, on each downward movement of 46 platen head 55 is first swung down by cam face 49 upon the article to be printed (while the concentric portion of cam slot 66 is traveling over roller 65) and then held in this operative position by cam 105 face 47 while the upper, non-concentric portion of cam slot 66 drives the ink roller up and along under the card 43^b, so that ink is forced through the stenciled portion of the 110 card onto the envelope or other article then held down against the card by said platen head. During the upward travel of T-cam 46, the above described operations are reversed and card 43^b is shoved out into a receiving magazine C (after platen 55 has 115 been raised), by the forward movement of the next card, 43^a, which is then shoved into printing position by the advance of card 43 which is being pulled out of magazine A by the card feed claws 74. 120

The timing of the card feed and inking impression operations, which permits the above stated sequence of operations, results from the differing angularities of the connecting rods 71 and 30 with reference to 125

their common crank 70, and from the fact that the amplitude of motion of the card feed claws 74 is greater than that dimension of the cards 43 which is parallel to the line of feed. Generally speaking the ink roller is coming back to its position of rest while the card feed claws are going forward to feed out a card, but the card feed lags behind the T-cam 46 by an amount represented by the crank angle and, in addition to this, when the claws 74 do begin to feed out card 43 from the bottom of magazine A, said card moves some distance before striking the next card 43^a ahead of it, and, through said card 43^a beginning to eject card 43^b from printing position. By that time roller 50 has run off section 47 of the cam face on 46 and is on section 49, so that platen head 55 has begun to lift and card 43 is free to move.

Normally the operation of the machine is not continuous. The clutch 10 is normally thrown out of engagement at the end of each complete revolution by a cam-shaped throw-out member 72 pivoted at the back of the main frame, as shown in Fig. 1^a, and engaging spring-pressed pin 10^a to withdraw it from engagement with dog 10^b on the hub of pulley 6, and, when so thrown out, leaves the parts in the position of rest shown in Figs. 1 and 1^a with cam member 46 and platen 55 raised, and with a card 43^b in printing position ready for the next cycle. Each card 43 has an extension 58 on the forward part of its frame, as shown in Fig. 11, on which is maintained a record of the customer whose address is given by the stenciled portion of the card, and as this extension projects from under the platen head 55 the operator can read said record, and if he then wishes to send the catalogue, or other article he is handling, to said customer he presses down on pedal 17 (Figs. 1, 1^a and 8) which is pivoted at 18 and connected by link 97 (Fig. 1^a) and a special mechanism to throw-out member 72. This permits the clutch 10 to reengage and the machine then performs a printing operation and continues to feed, and print from, the cards as long as pedal 17 is held down. 43^c is a panel of specially prepared paper in each card which can be stenciled in a typewriting machine.

Spring 19 returns clutch throw-out member 72 to normal position as shown in Figs. 1 and 1^a, and causes the machine to stop at the end of the current cycle whenever it is permitted to act by the operator removing pressure from both pedals 17 and 104.

The skip mechanism by which the operator can disable the printing mechanism by disconnecting platen 55 from the driving mechanism, while permitting the card feeding action to proceed, is operated by pedal 104 which is also connected to the clutch throw-out member 72 by link 97, and so is

able to pull down member 72, overcoming the resistance of spring 19. Downward motion of pedal 104, which is pivoted at 105 (Fig. 8) to the oscillating pedal yoke 89 in line with the pivot bearings 18 and 18^a for the latter, oscillates skip lever 108, which is pivoted on shaft 32, such motion being transmitted by link 107, pivoted to pedal 104 at 25. The free end of lever 108 is located under the pivot pin of cam roller 50, and, when raised by depressing pedal 104, moves said cam roller upward on its swinging support 51 away from, and out of engagement with, T-cam 46, so that vibration of said cam is not transmitted to platen head 55, and the latter remains at rest in its uppermost position. Consequently, the inking rollers reciprocate idly under the stencil cards as they come into printing position and no ink is forced through them and no printing is done even if an envelope or sheet of paper is held by the operator in printing position, because platen 55 does not move down to press such envelope against the stencil card beneath it. 106 is an adjustable stop carried on skip lever 108 and engaging link 107 to limit the upward movement of 107, and consequently also the upward movement of skip pedal 104 under the pull of its supporting spring 110^a.

It is evident that so long as both pedals 17 and 104 are connected to link 97, a brief downward pressure on pedal 17 will cause the machine to print from the card in printing position and, as spring 110 suspended from fixed pin 111 pulls pedal 17 up as soon as the operator's foot is removed, then stop at the end of that cycle. Also that if a brief downward pressure is given to the skip pedal 104, the machine will skip the card in printing position and stop at the end of that cycle as spring 110^a anchored on fixed pin 111^a pulls up that pedal; and that if either pedal 17 or 104 is held down continuously, the machine will accordingly print or skip continuously.

The object of the present invention is to introduce means whereby a selector apparatus may stop the machine when a card of a predetermined class reaches printing position, notwithstanding the fact that the operator is holding down either the printing pedal or the skip pedal. This consists of suitable apparatus (best shown in Figs. 6 and 7) for automatically breaking the connection between either pedal 17 or 104 and link 97 and comprises the lock lever 98 pivoted on the frame cross bar 23, and to which lever the lower end of link 97 is pivoted together with a pair of dogs 99, 99^a, pivoted at 100 to lever 98 and engaging notches 102, 102^a in links 101 and 101^a respectively pivoted to pedals 17 and 104. So long as these dogs are in engagement with their respective notched links, downward movement

of either pedal will be transmitted to link 97 and start the machine because each dog rests on a rigid stop 119 or 119^a cast on lever 98. Links 101, 101^a are normally held in engagement with dogs 99 and 99^a by tension springs 103, 103^a, but, if either of said links is swung away from its cooperating dog, the compression spring 109 or 109^a under said dog and pocketed in stop 119 or 119^a will swing it up into the position shown in Fig. 7, free from engagement with said notch. The means for thus freeing either link 101, 101^a from its cooperating dog comprise the trip bar 26 pivoted to the core 27 of solenoid 28, and having a notch 26^a (Fig. 1^a) adapted to engage either pin 118, set in the upper portion of link 101, or pin 118^a, set in the upper portion of link 101^a. Trip bar 26 is sufficiently flexible laterally to be moved by the operator grasping the loop 117 at its outer end to cause it to engage either of these said pins. When placed on either pin it is held down in such engagement by spring 11^a. If its notch 26^a is hooked over pin 118, it is evident that whenever the operator is running the machine with printing pedal 17 depressed and solenoid 28 is energized, link 101 will thereupon be pulled out of engagement with dog 99 and lock lever 98 will be permitted to rise, thus throwing clutch throw-out member 72 into operative position and stopping the machine at the end of the current cycle. Also if trip bar 26 engages pin 118^a, and the operator is running the machine and skipping cards by holding down pedal 104, any energizing of solenoid 28 will similarly pull link 101^a out of engagement with dog 99^a and thereby permit lever 98 to rise and similarly stop the machine.

The purpose of thus stopping the machine, with one of the selected cards in printing position, is to give the operator time in which to read the record on the extension margin 58 of said card and determine whether he will print from it or skip it. Thus if the selected class of cards with which the selector device has been set to operate contain the addresses of hardware merchants, the order to the operator may be that mail matter shall be sent only to such hardware merchants as may have purchased \$50.00 worth of goods during a given prior period, and consequently the operator will have to read the record on the card to determine whether he shall print from it or skip it. If he has been running the machine with the skip pedal 104 down and the trip bar 26 connected with pin 118^a, link 101^a will have been pulled out of engagement with dog 99^a and the machine thereby stopped. If the operator finds on reading the record on the card in printing position that he should address an envelope or wrapper to this particular hardware merchant,

he will momentarily press down printing pedal 17, thus pulling down the clutch throw-out member 72 and causing the machine to make one revolution and print from that card, the transferring of his foot from pedal 104 to pedal 17 having released the former and thereby reestablished the connection with the platen 55 by allowing cam roller 50 to drop into operative position. After printing from this card, the operator will transfer his foot to pedal 104 and the machine will continue skipping cards as before until another one comes along having the particular notch or arrangement of notches which corresponds to the predetermined classification.

If, however, a reading of the record on the card shows that the customer's purchases have not reached \$50.00 and the operator accordingly should skip it, he must reestablish the skipping connection and, to do this, he presses upon resetting button 115 on the end of connecting rod 114, (Figs. 1 and 1^a) the lower end of which is journaled in the free end of link 113 pivoted on pin 100 on which both dogs 99 and 99^a are mounted, and, this rod 114 having its lower end 112 extending over both dogs, as best shown in Fig. 6, this downward pressure of button 115 will force down whichever dog has been tripped and cause it to reengage its cooperating link. In the case assumed, the dog so first tripped and afterwards reset, will be 99^a. On removal of pressure from button 115, spring 116 will lift the resetting rod and reestablish normal conditions. Thereupon the operator can again press down pedal 104 (or continue to hold it down, if he has not taken his foot off of it) and the machine will again start into operation, skipping cards as before, until another card with the proper notch or arrangement of notches again trips the clutch.

If, on the other hand, the operator is running the machine with the printing pedal down and the trip bar 26 in engagement with pin 118, the arrival of a card of the predetermined class, or classes, will pull link 101 out of engagement with dog 99 and the operator will then either step on skip pedal 104 to skip that card, or, if he wishes to overrule the automatic selection of the machine, reset the connection to pedal 17 by means of pressure on the button 115 and thus cause the machine to resume operation as before. In either case, the automatic trip disables the pedal which is then in use so that the operator can accomplish nothing by moving it up or down until he has first reestablished its connection to the clutch throw-out either by depression of the other pedal, or by pressure upon the resetting button 115. The reason why either dog, as 99, will not reengage its cooperating notch in link 101 until the lock lever 98 has been first pulled down by the

other pedal, or the dog forced down by the reset pin 112, is because such dog is thrown upward by its spring 109 as soon as released from its cooperating notch as indicated in Fig. 7.

The selector apparatus comprises a series of feeling fingers 34 cooperating with stencil cards having a corresponding series of notches such are shown at 44, 44^a, 44^b, in Fig. 11. When any one or more of the fingers 34 fall into one or more of the notches of the cards as the latter are fed along the card guides 36 and reach the position shown at 43^a in Fig. 2, the dropping of any one finger into such a notch closes the electric circuit which energizes solenoid 28 to trip the main clutch 10 and cause the machine to come to a stop at the end of the current cycle.

The particular arrangement of apparatus for closing the electric circuit 29 through battery 33 and solenoid 28 is best shown in Figs. 3, 4 and 5. There are as many notches 44, 44^a, etc., as can be conveniently cut in a card and the same number of fingers 34. Each notch may represent a class of cards, and combinations of two or more may represent additional classes. Each finger 34 is independently pivoted at 35 on an individual housing 157, all of the housings 157 being rigidly supported upon the main selector housing 8 which is supported over the card guides between the magazine A and the printing mechanism B. Housing 8 is fastened to the guides by screws 8^a engaging slots 8^b therein. This permits the housing to be adjusted in position so that fingers 34 will have their lower ends exactly over notches 44, in the card which is in position 43^a. Each finger is connected to its housing 157 by a tension spring 9, which is fastened to the finger at one end and to pin 57^a in the housing at the other. Said pin 57^a also engages the arc-shaped slot 34^a in a finger and so serves as a stop to limit the finger movement. When the finger is down in one of the operative positions as shown in full lines in Figs. 4 and 5, spring 9 tends to pull it into the lowermost of said positions as shown in full lines in Fig. 5. When any particular finger is not in use it is swung up into the vertical position shown in dotted lines in Fig. 5 and also in full lines in Fig. 4, and is also held in this vertical position by the same spring 9, as indicated in dotted lines in Fig. 5. Each finger 34 has a rearwardly extending lug 11 which cooperates with a dog 12 on shaft 39, on the outer end of which is mounted the hammer 40 for forcing spring contact strip 38 intermittently against stationary contact screw 37, thereby closing the electrical circuit 29, unless the switch 68 therein is open (see Fig. 4). 42 is a back stop for hammer 40 preventing it from swinging so far to the left that dogs 12

will turn beyond the zones of motion of lugs 11.

When the machine is at rest, all of the fingers 34 in use are supported in the upper operative position, shown in full lines in Fig. 4 and in broken lines in Fig. 5, by means of the oscillating cam bar 13, pivoted at 14 in housing 8 and oscillated by crank 15 connected by link 16 to short crank 65^a on the pivot shaft 63 of the ink roller operating lever 62—64. When, however, the T-cam 46 has been pulled down far enough to begin operating the inking roller by reason of the fact that cam roller 65 has entered the upper portion of cam slot 66, and the platen 55 has been lowered and the printing operation is in progress, the upward motion of the short crank 65^a (coincident with the movement of inking lever 62) oscillates cam bar 13 into the full line position shown in Fig. 5. This permits the finger or fingers in operative position to drop into any notch 44 thereunder, as shown in Fig. 5, and to so close electrical circuit 29, as before described, thus energizing solenoid 28 and causing it to break the connection from the pedal in use to the clutch throw-out member 72, with the result that the latter rises under the pull of spring 19 and, when the current cycle of operations of the machine is completed, trips the clutch and stops the machine. Before this cycle is completed, however, the upward swing of the T-cam 46 has caused the lifting of platen 55, thus releasing the card from which the printing has been done, and the second half of the rotation of the main crank 7 has driven the feed claws 74 forward, feeding the card 43^a, with which finger 34 has cooperated, forward into printing position, and this card 43^a has kicked card 43^b out of the printing zone into the receiving magazine C. If, however, when the finger or fingers in operative position have been allowed to drop by this oscillation of cam bar 13, there is no notch 44 under said finger, it will then rest on the card frame before it has moved far enough to cause its lug 11 to oscillate hammer 40 and close circuit 29, and the solenoid will not be energized and the clutch throw-out mechanism not operated.

To insure conjoint action of a series of the fingers 34 so that none of them will drop unless all of them register with card notches, the fingers in operation may be tied together by the pin 34^a extending through them and through the swinging yoke 69 which is pivoted at 69^a in housing 8 in line with the pivots 35 of all the fingers. Oscillating cam bar 13 also operates on this yoke and even if only one finger 34 is in working position it may be pinned to the yoke by 34^a.

To further extend the number of possible combinations of notches of any one card, we employ one or more spring metal clips 59, as

shown in Figs. 11 and 12, which are adapted to snap over the edge of the extension 58 of the card frame and brings their inwardly turned free ends in the holes 59^a opposite the 5 notches 44, 44^a, 44^b, etc. Each such clip 59 is wide enough to cover any particular notch over which it may be placed and thus in effect blank it out. Thus if it becomes necessary to disable a certain finger 34 which 10 comes opposite a notch 44^b, in cards which are not to actuate the selector, although they have notches 44^b which would normally permit such finger to drop, this can be done by covering said notches in each such card by 15 one of the clips 59, as shown in Fig. 11. These clips are made of such thin metal that they do not appreciably separate adjacent cards and still they are firmly fastened to any particular card by their bent inner 20 spring ends hooking into anchoring holes 59^a.

The apparatus which permits the machine to repeat, i. e. print successively a series of copies from one stencil card held in the printing zone, consists essentially of a pedal-controlled mechanism for totally disabling the card feed claws 74 during any desired number of cycles and positively breaking the electric circuit 29 during such period so that the clutch throw-out cannot be operated 25 while the repeat pedal is held down. This apparatus is best shown in Figs. 8, 9 and 10. The repeat pedal 76 is pivoted at 88 in the yoke 89 which is integral with printing pedal 17. As shown in Fig. 1^a, the pedal 76 has a 30 downwardly and backwardly extending elbow 90 which carries an adjustable contact bolt 91 so that, when pedal 76 is pressed downward, the pedal yoke 89 and printing pedal 17 will also be vibrated to withdraw 35 the clutch throw-out cam 72, if said printing pedal is in gear, and thereby cause the printing mechanism to operate through consecutive cycles as long as pedal 76 is held down. When, however, printing pedal 17 is pressed 40 down for any other kind of printing operation the repeat pedal 76 will merely oscillate idly on its moving pivot 88 and on its supporting link 87, without interfering with the normal operation of the machine as hereinbefore described.

The particular preferred claw disabling apparatus herein illustrated comprises a pivoted mounting for claws 74 at 78 on the sliding carriage 75 and means under control of 45 pedal 76 for elevating the rear ends of the claws, and consequently depressing the claws proper, so that they will not engage the bottom card 43 in magazine A, but will reciprocate idly back and forth thereunder, thus 50 leaving the card 43^b in the printing zone undisturbed. As shown, the rear ends of the claws 74 are connected by a back bar 81 which carries an anti-friction roller 82 on a depending lug. Normally, the back bar 81 55 is held down upon the adjustable stop 79 by

the claw supporting springs 80, and the claw grasps the bottom card in the magazine at each reciprocation. When, however, the disabling track 83, supported on swinging yoke 84, is lifted under roller 82, and forces it up, 70 the front end of claw 74 is tipped down so that it will not engage a card. During any period in which pedal 76 is depressed, roller 82 runs back and forth on track 83. Yoke 84 is pivoted on shaft 85, mounted on housing 75 86, and interlocks with the yoke 84^a at joint 84^b (see Fig. 2), the outer end of yoke 84^a being pivoted to link 87 which extends down to repeat pedal 76. An adjustable stop for limiting the upward movement of link 87 is 80 shown at 92. This stop is so adjusted that it will permit downward movement of yoke 84 sufficient to free track 83 from roller 82 and leave the claw 74 free to operate in the normal way. Carriage 75 slides on guide 85 rods 77, 77.

To break the circuit 29, when repeat pedal 76 is depressed, we employ a circuit breaker comprising the contact pins 20 and 21 mounted in a block 95 of insulating material fastened by screw 96 to the housing 95^a depending from the main frame. Pin 21 is normally forced down by spiral spring 21^a, its downward motion being limited by adjusting nuts 24. Spiral spring 20^a tends to 95 force pin 20 also downward so as to leave a gap between the two pins which will break circuit 29; but, when disabling track 83 is lowered and claw 74 therefore allowed to operate normally and feed out cards, the projecting arm 22 carried by yoke 84 is raised under pin 20 and forces it up into contact with pin 21, thus closing the circuit 29. Springs 93 and 94 normally hold arm 22 in this raised position, shown in broken lines in 100 Fig. 9 and thus close the circuit, also holding down the disabling track 83 out of operative position, but when pedal 76 is pressed down the pressure of arm 22 is removed from pin 20 and the latter is then forced down by 105 spring 20^a away from contact with pin 21.

To prevent the disabling track 83 from falling back into normal position at some period in a cycle of operations when the machine is set for repeating, which would 110 permit the claw 74 to rise and feed cards forward, thus discharging the card in printing position from the machine before the desired number of impressions may have been taken therewith, as might happen if the operator inadvertently took his foot off of the repeat pedal 76 some time during the first half of a cycle, we employ the device best shown in Fig. 10 in which 120 is a holding dog pivoted to the main frame at 115 121 and pressed by spring 122 under lever 84 whenever track 83 is raised to disable the feed claw. This dog 120 normally rests against the side of lever 84, as shown in 125 Fig. 10, when track 83 is down in normal 130

position, as there shown, and the card feed is operating in the usual way. Under these conditions, the arm or finger 125 rigid on pivot shaft 32 and vibrating back and forth with bell crank 31 just touches finger 123 pivoted at 124 to a projection from dog 120. When, however, track 83 has been raised by pressing down repeat lever 76, dog 120 is pushed under lever 84 by spring 122 and holds track 83 raised until the end of the current cycle at which time the card feed claws 74 are in their extreme right hand position. The last portion of this feeding movement of the claws, however, has swung arm 125 in a clockwise direction far enough to strike finger 123, which has been swung slightly to the left by the dropping of dog 120 by which it is carried, and then, and then only, is dog 120 swung back by this action to the position shown in Fig. 10, permitting track 83 to drop, and allowing claws 74 to rise into operative position. As a result, these claws are so put back into operative position only at the end of a complete cycle when if the operator has inadvertently taken his foot off pedal 76, the machine will stop and he can resume repeating, if he wishes to do so, from the same card, by again stepping on pedal 76, or if he has printed the necessary number of copies from that card, he can resume printing or skipping operations by pressing pedal 17 or 104 as before described. If this device is not used, the removal of pressure from pedal 76 at any time during the first half of a cycle would have permitted track 83 to fall and claw 74 to rise in time to resume feeding and discharge the card then in printing position, thus rendering it impossible for the operator to get said card back into printing position and resume printing therefrom, if his release of pedal 76 was inadvertent, or premature.

To provide for the contingency of arm 125 traveling so far to the right (looking at Fig. 10) that it would pass under and beyond finger 123, the latter is pivoted to dog 120 by a knuckle joint which permits it to swing to the left, in a clockwise direction when arm 125 swings back again, but to drop back into operative position before arm 125 swings forward again in the next cycle. That is to say, when arm 125 engages finger 123 on the forward stroke of the feed claw that finger and the dog 120 swing as a unit on pivot 121, but on the return movement of arm 125, finger 123 swings alone on its pivot 124. The fact that dog 120 is thus swung up into the position shown in Fig. 10 at the end of each cycle of the machine does not interfere with repeat printing while pedal 76 is being held down because lever 84 is held up by said pedal 76 during such repeat operations. It is only when the operator has taken his foot off

pedal 76 that this movement of dog 120 permits track 83 to drop at the end of the current cycle, and thereby permit pedal 76 to rise and stop the machine at the end of the cycle while at the same time restoring claws 74 to operative position.

In operating our invention, if the stack of stencil cards in magazine A contains a large number of cards of the class or classes to be used, so that a good deal of printing has to be done with them, the trip bar 26 will be hooked over pin 118 so as to attach the selective device to the printing pedal 17 and the operator will start the machine by pressing down said pedal. In such case all fingers 34

corresponding to notches in cards of still other classes, which are not to be printed from, will be turned down in operative position, but not tied together with pin 34^a. All cards then fed out of the magazine which do not have a notch 44 corresponding to one of the classes which are to be skipped, will accordingly be fed through the machine and printed from in the usual way. (Under these conditions it would probably happen that there would be a number of classes of cards which were to be skipped and, if so, a corresponding number of fingers 34 would be put down in operative position but not tied together by the cross pin 34^a.)

When a card of any of these several classes not to be used comes along, the corresponding finger 34 will drop into its notch and the machine will be stopped. Thereupon the operator can look at the record on the card and, if there is no reason for overruling the action of the machine, he will step on pedal 104

which will pull down lock lever 98 and clutch throw-out member 72, and also swing cam roller 50 away from cam 46, with the result that the machine will again start into operation, feed that card through without printing therefrom, and stop at the end of that cycle (the operator having given pedal 104 only a momentary depression). The

pulling down of lock lever 98 by pedal 104 will have given dog 99 a chance to reengage notch 102 in link 101 which has previously been returned to normal position by spring 103, the pull of solenoid 28 having been exerted only momentarily while a finger 34 was down in a notch 44. The contact between contact screw 37 and spring contact 38 having been broken either by the movement of the card or by the tipping up of cam bar 13, or by both actions, some time before the cycle was completed, link 101

has been freed from any pull of the solenoid and has been pulled against dog 99 by spring 103 before said dog has been lowered by the downward swing of lock lever 98 produced by pedal 104. The result is that the attachment has been reset with both dogs 99 and 99^a in engagement with their cooperating links 100, 101^a and consequently with

both pedals 17 and 104 connected to the clutch throw-out. Therefore when the operator again presses down on pedal 17 the machine starts again to print from all cards presented to it until a card of one of the exempt classes again reaches printing position and the above described procedure is then repeated.

If, however, on examination of any of the cards which thus stop in printing position the operator decides to overrule the decision of the machine, he presses down on resetting button 115, thereby causing dog 99 to re-engage its link 101 without pedal 104 having to be first pressed down, and thereupon he may stop on pedal 17, and cause the machine to resume operations, beginning by a printing from this particular card which the machine would have rejected but which the operator has decided to use after his attention has been called to it by the automatic stopping of the machine.

If the stack of cards to be used contains only a small percentage belonging to the class or classes from which printing is to be done, more rapid work can be done if the above described arrangement is reversed and the attachment is set by hooking trip bar 26 over pin 118^a and then starting the machine by holding down skip pedal 104. In such cases the finger or fingers 34 corresponding to notches representing the class or classes to be printed will be put down in operative position, but not pinned together. Then, as cards of other classes are fed out, the electric circuit 29 will not be closed and the machine will run on skipping them until one of the class to be used appears, whereupon the solenoid 28 will be energized, link 101^a pulled out of engagement with dog 99^a, and lock lever 98 and cam lever 72 be permitted to rise, the latter throwing out clutch 10 at the end of that cycle and leaving this card exposed in printing position 43^b. If, on inspecting said card the operator finds that the decision of the machine was right, he releases pedal 104 and presses down pedal 17 momentarily, thus starting the machine, causing it to print from that card and to stop at the end of the cycle. He next presses down skip pedal 104 again, and the previously described operations are resumed. If, however, he decides to overrule the decision of the machine, he resets dog 99^a by pressing down on button 115 and the machine starts, when pedal 104 is pressed down again, skipping said card and all succeeding cards until another member of the class from which printing is to be done arrives.

In normal operation the pedal in use should be permitted to rise before the resetting button 115 is pressed down and then only its corresponding dog will have to be manipulated by downward pressure on said

button in the resetting operation, but it may be possible to reset while the pedal is still held down, if the button 115 can be pushed down far enough and hard enough to also carry down the other dog, and possibly lock lever 98 with it, in order to get the first trip dog down far enough to cause it to re-engage the notch in its cooperating link while the latter is in depressed position resulting from the pedal to which it is pivoted being held down.

In both cases above described, the cards in a plurality of classes may be thus selected by the machine for examination by the operator by putting a corresponding number of fingers 34 down in operative position without tying them together by pin 34^a. If only one class is to be selected, then only one finger is put down, or a number of fingers tied together corresponding to the combination of notches which represents that one class.

When a card arrives at printing position from which a number of impressions are to be taken, the operator presses down pedal 76 as before explained. This, by operation of elbow 90 and set screw 91, also vibrates pedal yoke 89 and lowers printing pedal 17, unless that pedal is already in depressed position. In either case, the movement of pedal 76 lifts claw-disabling track 83 under roller 82 and thereby lowers claw 74 to a point such that the continuous operation of the machine resulting from the lowering of printing pedal 17 will then not feed out any more cards. Accordingly, any number of envelopes or wrappers or other articles may be consecutively inserted beneath the vibrating platen 55 and all printed from the same card then in position 43^b. At the same time circuit 29 is broken by the separation of contact pins 20 and 21, due to the lowering of pressure arm 22 in the manner previously described, and the trip mechanism will not be operated during this "repeat" printing because solenoid 28 will not be energized, even if the next card, in position 43^a, should have a notch co-operating with a finger 34 down in operative position over it and dropped into said notch during each cycle of operation of the machine. Whenever the foot is taken off pedal 76 it will be raised by springs 93 and 94, circuit 29 will be closed and claw 74 allowed to rise into normal card feeding position.

Among the advantages of our present invention may be mentioned the following: As compared with the particular embodiment of the general idea illustrated in our prior Patent No. 1,578,912, the present mechanism is smoother and less noisy in operation. Also it requires the operator to constantly keep his foot on one of the pedals, which insures closer attention to his work. The present machine is practically fool-proof in

that, when it is stopped by the selecting device, the operator cannot inadvertently restart it to do the wrong thing by further manipulating the pedal he has theretofore 5 been holding down. That pedal has then become disconnected, and the only thing he can accomplish by pedal manipulation is either to do the particular thing for which the attachment has been automatically set, or 10 to operate the repeat device,—which latter is rarely required. Consequently he cannot easily make any mistake. The selector can be easily cut out by opening switch 68, and then the machine can be manipulated in the 15 usual way solely by positive action of the operator, as described in the prior Belknap Patent No. 1,256,509. The selector is positive in operation and usually the fingers 34 are not dragged over the stencil cards, be- 20 ing lifted and held up by cam bar 13 all the time the cards are in motion. This saves wear on the cards. A multiplicity of selective actions are possible, employing a multiplicity of fingers, with only one contact 25 device 38, 37 for all the fingers, and that device is so far removed from the cards, and envelopes being printed, that any arcing there creates no objectionable fire risk. The movement of contact hammer 40 is so rapid, 30 on account of its long radius of oscillation, that the circuit closing and breaking actions are always rapid, and arcing thereby practically eliminated. The whole of the clutch manipulating mechanism is located in the 35 rear of the machine, as best shown in Fig. 1, so that the operator can sit with his feet well under the table and his body close to his work of feeding envelopes or wrappers to the printing mechanism. Finally, the en- 40 tire attachment can be easily applied to the standard machines of the prior Belknap patent now in use, the finger housing 8 with fingers and circuit controller being a complete, detachable unit which can be placed 45 on the table of any such machine, and the solenoid and clutch tripping mechanism being easily installed on the lower frame of such a machine, or taken off whenever no longer used.

50 While we have shown our invention as applied to an apparatus involving stencil cards as an element of the printing mechanism, it is evident that other forms of address bearing strips may be substituted for such stencil cards and that other changes in the details 55 of the preferred form of apparatus herein described and illustrated could be made without departing from the principle of our invention so long as some or all of the essential novel features and functions are retained 60 to produce substantially the same result in substantially the same way.

Another feature of advantage in our invention arises from the fact that none of the 65 selective fingers 34 is at any time allowed

to rest on a card while said card is in motion. This results from the fact that the rotation of cam bar 13 back toward dotted line position (Fig. 5) far enough to lift any fingers 34 which may be in operative position out of the 70 card notches and above the plane of the upper card surface before the card in position 43^a is fed forward by the card 43 which is being pulled out of the magazine behind it. This retarded feeding forward of card 43^a 75 with reference to the movement of the printing mechanism (which operates cam bar 13) is due to the cumulative effect of the relative angularity of the connecting rods 71 and 30, and of the delay resulting from the fact that 80 the travel of the card feeding claws 74 is greater than that dimension of each card which is parallel to the line of feed, so that card 43 moves some distance before it comes in contact with card 43^a, all as previously 85 explained herein.

Having described our invention we claim:

1. In an addressing machine having mechanism for feeding a series of address bearing strips to and through a printing 90 zone, a driving mechanism for said machine, a movable member adapted to disconnect said driving mechanism from said feeding mechanism, and a pedal connected to said movable member, the combination, with said 95 above described apparatus of means for automatically breaking said pedal connection whenever a strip of a predetermined character reaches printing position, whereby the operator has time to then examine 100 said strip before again starting the machine.

2. A combination such as defined in claim 1 in which said driving mechanism comprises a one-revolution clutch, and said movable member is normally spring-held in a 105 position to throw out said clutch at the end of each cycle of strip feeding.

3. A combination such as defined in claim 1 in which the connection between said pedal and said movable member includes a dog 110 operatively connected to the latter, and a swinging link operatively connected to said pedal and detachably engaging said dog.

4. A combination such as defined in claim 1 in which said means for automatically 115 breaking said connection comprises an electro-magnet and a device for energizing said magnet actuated by strips of the selected class.

5. An apparatus such as defined in claim 1 120 combined with means separate from said pedal but under control of the operator for reestablishing said previously broken connection.

6. An apparatus such as defined in claim 1 125 combined with means separate from said pedal but under control of the operator for reestablishing said previously broken connection, said means comprising a push button and a device connected thereto engag- 130

- ing one of the cooperating elements included in said connection.
7. In an addressing machine having mechanism for feeding a series of address bearing strips to and through a cooperating apparatus forming with said strips a printing mechanism, a driving mechanism for said machine, a one-revolution clutch in said driving mechanism, a cam adapted, when in raised position, to trip said clutch at the end of each cycle of operations, two pedals beneath and connected to said cam, and means connected to one pedal for disabling said printing mechanism when that pedal is depressed, the combination, with said above described apparatus, of means adapted to break the connection from either pedal to said cam; whereby the machine may be automatically stopped at the end of any cycle whether one pedal is being held down to print from consecutive strips or the other pedal is being held down to feed successive strips through the machine without printing therefrom.
8. A combination such as defined in claim 7 in which said last mentioned means comprises two swinging links, one pivoted to each pedal and both adapted to swing into or out of engagement with a member connected to said cam, and a reciprocating trip bar adapted to be detachably connected to either of said links.
9. A combination such as defined in claim 7 in which said last mentioned means comprises two swinging links, one pivoted to each pedal and both adapted to swing into, or out of, engagement with a member connected to said cam, and a reciprocating trip bar adapted to be detachably connected to either of said links, together with an electro-magnet adapted to reciprocate said bar when energized.
10. A combination such as defined in claim 7 in which said last mentioned means comprises two upright swinging links each pivoted at one end to a pedal and provided with a laterally projecting pin at its other end and both adapted to swing into or out of engagement with a member connected to said cam, and a longitudinally reciprocating, laterally adjustable, trip bar having a notch adapted to slip over either of said pins.
11. A combination such as defined in claim 7 in which said last mentioned means comprises two upright swinging links each pivoted at one end to a pedal and provided with a laterally projecting pin at its other end and both adapted to swing into or out of engagement with a member connected to said cam, and a longitudinally reciprocating, laterally adjustable, trip bar having a notch adapted to slip over either of said pins, together with an electro-magnet adapted to reciprocate said bar when energized, a normally open current supply circuit and a device for closing said circuit operated by certain of the address bearing strips when approaching printing position.
12. In an addressing apparatus comprising inking and impression mechanisms, a series of address bearing strips, mechanism for feeding said strips successively to said inking and impression mechanisms, and means under control of the operator for temporarily disabling said feeding mechanism but positively maintaining said inking and impression mechanisms in operation, whereby repeated printing from any one strip may be effected, the combination, with said above described apparatus, of a selecting device which determines whether the machine shall print from or skip each successive card and mechanism automatically disabling said selecting mechanism during any period of operation of said repeating means.
13. A combination such as defined in claim 12, in which said selecting device is electrically operated and the functioning of said repeating means automatically breaks the current supply circuit to said selecting device.
14. A combination such as defined in claim 12, in which said repeating means comprises a reciprocating, pivoted feed claw and a vertically swinging track which, when raised, tilts said feed claw out of operative position, and in which said selecting device is electrically operated by a circuit having a normally closed circuit breaker therein, said circuit breaker being opened when said track is lowered out of engagement with said claw.
15. An addressing apparatus comprising, in combination, a series of stencil cards having varied classification features, inking and impression mechanisms, means for feeding said cards successively to and through said inking and impression mechanisms, a prime mover for all the above mentioned apparatus, a movable member adapted to disconnect said prime mover from said apparatus, a pedal normally connected to said member, and a device for automatically breaking said connection whenever one of said cards having classification features of a particular class reaches printing position; whereby the operator may examine said card at leisure before reestablishing said connection and restarting the apparatus.
16. A combination such as defined in claim 15 in which said first mentioned means comprises a one-revolution clutch, and said movable member is normally spring-held in a position to throw out said clutch at the end of each cycle of card feeding.
17. A combination such as defined in claim 15 in which the connection between said pedal and said movable member includes a

swinging link permanently pivoted to one of said elements and detachably connected to the other.

18. A combination such as defined in claim 5 in which the connection between said pedal and said movable member includes a dog operatively connected to the latter, and a swinging link operatively connected to said pedal and detachably engaging said dog.
19. A combination such as defined in claim 15 in which said means for automatically breaking said connection comprises an electro-magnet and a device for energizing said magnet actuated by strips of the selected 15 class.

20. An apparatus such as defined in claim 15 combined with means separate from said pedal but under control of the operator for reestablishing said previously broken connection.

21. An apparatus such as defined in claim 15 combined with means separate from said pedal but under control of the operator for reestablishing said previously broken connection, said means comprising a push button and a device connected thereto engaging one of the cooperating elements included in said connection.

22. An addressing apparatus comprising, 30 in combination, a series of stencil cards having varied classification features consisting of notches in their edges and legends written on their upper faces, inking and impression means forming, with said cards, a printing mechanism, means for feeding said cards successively to and through said mechanisms and optionally operating said impression mechanism, a prime mover for all said above described apparatus, a one- 40 revolution clutch connecting said prime mover to said apparatus, a movable member adapted to trip said one-revolution clutch, a pedal normally connected to said member, and a device for automatically breaking said connection whenever one of 45 said cards notched in a certain manner reaches printing position; whereby the operator may then examine the legend thereon and decide before reestablishing said connection what further operation he will perform with said card.

23. An addressing apparatus comprising, 55 in combination, a series of stencil cards having varied classification features consisting of notches in their edges and distinguishing characteristics appearing on their upper faces, inking and impression means forming, with said cards, a printing mechanism, means for feeding said cards successively to 60 and through said mechanisms and optionally operating said impression mechanism, a prime mover for all said above described apparatus, a one-revolution clutch connecting said prime mover to said apparatus, a cam adapted, when in raised position, to trip said

clutch at the end of each cycle of the feeding operation, two pedals beneath and normally connected to said cam, a device connected to one of said pedals for disconnecting said impression mechanism when said pedal is depressed, and means adapted to automatically break the connection from said cam to whichever pedal is being held down by the operator whenever one of said cards notched in a certain manner reaches printing position; whereby the apparatus may then be automatically stopped at the end of the current cycle whether one pedal is being held down to print from consecutive cards through the machine without printing therefrom and, in either case, the operator may then read the legend on said card and decide before again starting the apparatus, whether to skip it or print from it.

24. A combination such as defined in claim 23 in which said last mentioned means comprises two swinging links, one pivoted to each pedal and both adapted to swing into or out of engagement with a member connected to said cam, and a reciprocating trip bar adapted to be detachably connected to either of said links.

25. A combination such as defined in claim 23 in which said last mentioned means comprises two swinging links, one pivoted to each pedal and both adapted to swing into or out of engagement with a member connected to said cam, and a reciprocating trip bar adapted to be detachably connected to either of said links, together with an electro-magnet 100 adapted when energized, to reciprocate said bar.

26. A combination such as defined in claim 23 in which said last mentioned means comprises two upright swinging links each pivoted at one end to a pedal and provided with a laterally projecting pin at its other end and both adapted to swing into or out of engagement with a member connected to said cam, and a longitudinally reciprocating, laterally adjustable, trip bar having a notch 110 adapted to slip over either of said pins.

27. A combination such as defined in claim 23 in which said last mentioned means comprises two upright swinging links each pivoted at one end to a pedal and provided with a laterally projecting pin at its other end and both adapted to swing into or out of engagement with a member connected to said cam, and a longitudinally reciprocating, laterally adjustable, trip bar having a notch adapted to slip over either of said pins, together with an electro-magnet adapted, when energized, to reciprocate said bar, a normally open current supply circuit for said magnet and a device for closing said circuit operated by certain of the address bearing strips when approaching printing position.

28. In a selective device for use with a series of cards or similar objects being forced 130

along suitable guides, the combination of a series of independently pivoted fingers located above said cards, a common movable member adapted when in normal position to hold any of said fingers resting upon it slightly above said cards, and connections for moving said member into another position which will allow any finger resting on it to fall far enough to touch the card beneath and enter any recess in said card registering with such finger.

29. A structure such as defined in claim 28 combined with a yoke extending under all said fingers and having pivot bearings in line with said finger pivots and also resting on said movable member, and means for pinning any number of said fingers together and to said yoke, whereby none of the fingers so pinned together may enter any recess in a card beneath it unless said card also has recesses registering with all the other fingers of the group.

30. In a selective device for use with a series of cards or similar objects being forced along suitable guides beneath such device, the combination of a series of mutually independent fingers pivoted on a common axis and adapted to be dropped into engagement with recesses in the cards beneath, an electric circuit controller, a rotatable shaft adjacent said fingers adapted to operate said electric circuit controller by its rotation, and means by which the dropping of any finger into a card recess will cause said shaft to so rotate.

31. A selective device for use with addressing machines having card guides and means for feeding a series of cards along the same, which said device comprises a housing adapted to be fastened on said guides over said cards, a series of mutually independent fingers all pivoted in said housing and each adapted to drop into any suitable recess in a card beneath it, a single electric circuit controller also mounted in said housing, and means whereby the dropping of any finger into a card recess will operate said circuit controller.

32. A structure such as defined in claim 31 combined with an oscillating, finger-supporting cam-bar also journaled in said housing, and connections for intermittently oscillating said cam-bar, whereby the ends of said fingers are normally held above the plane of the upper surfaces of said cards except when said cam-bar is oscillated into a particular position.

33. A structure such as defined in claim 31 combined with a series of springs connected respectively to said fingers and adapted to press the same downward when they are swung into their operative positions, and also to hold said fingers out of operative position when the same are swung upward.

34. A combination such as defined in claim 31 in which the fastening means for said housing permit horizontal adjustment thereof on said guides.

35. In an addressing apparatus employing a series of address bearing strips and having inking and impression mechanisms, guides, means for feeding said strips along said guides and for operating said mechanisms, and a series of address bearing strips adapted to be fed along said guides to said mechanisms, which strips are provided with variously located notches representing different classifications, the combination, with said apparatus, of a selective device mounted over said guides comprising a series of fingers adapted to drop into said notches, a movable member on which all of said fingers in operative position rest, and a connection from said member to said inking mechanism by which said member is moved into position to permit said fingers to drop into said notches only when said inking mechanism is in action.

36. The combination with a structure such as defined in claim 35, of a clip adapted to be mounted on one of said strips and then cover one of the notches therein.

37. In an addressing machine comprising a series of stencil cards, some of which have notches in their edges, guides for said cards, means for feeding said cards along said guides, and a selective device comprising a series of fingers mounted over said guides and adapted to drop into certain of said notches as said cards are fed beneath them, the combination, with said above recited mechanism of a plurality of removable clips adapted to be mounted on said cards and to then cover certain of said notches, whereby the placing of one of said clips over any particular notch will then prevent any of said fingers from falling into such notch when said card comes beneath it and thereby modify the action of said selective device.

38. In an addressing machine having mechanism for feeding a series of address bearing strips to and through a printing zone, a prime mover for said mechanism, and a pedal connected to said mechanism adapted to maintain it in operation so long as said pedal is held in a certain position, the combination, with the above described apparatus, of a device automatically actuated by any member of a particular class of said strips to break said pedal connection whenever a strip of said class reaches said printing zone.

39. A combination such as defined in claim 38 in which said pedal connection comprises two normally interlocking elements, one of which is connected to said pedal, and in which said automatic device is operatively connected to one of said elements.

40. In an addressing machine having mechanism for feeding a series of address bearing strips to a printing zone, an automatic selector cooperating with each strip to determine what shall be done with it after reaching said zone, and a device under control of the operator for producing repeated printing from any one of said strips, the combination, with said above described apparatus of means for automatically disabling said selector while said repeating device is in operation.

41. In an addressing apparatus employing a series of address bearing strips and having mechanism for either feeding and printing from said strips consecutively or for holding any one strip in printing position during a plurality of feed cycles, the combination, with said apparatus, of automatic means for disabling said strip feeding mechanism until the end of any one cycle of operations if it has been disabled by the operator at an earlier period in said cycle.

42. In an addressing apparatus comprising a series of address bearing strips, inking and impression mechanisms, a pivoted reciprocating claw normally feeding said strips to said mechanisms, means for reciprocating said claw, and a device for disabling said claw by adjusting it in a position such that it will not engage said strips during its normal reciprocation, the combination, with said apparatus, of a dog adapted to normally hold said claw in disabled position and an attachment adapted to trip said dog only when the claw feeding motion is nearly completed, whereby any restoring of said claw to operative adjustment at any earlier period is automatically prevented.

43. A combination such as defined in claim 42 in which said attachment comprises a rigid member reciprocating with said claw, and a finger pivoted on said dog, projecting into the path of said rigid member, and adapted to swing on its pivot only in the direction of the return motion of said claw.

44. In an addressing apparatus comprising a series of address bearing strips, printing means employing said strips, a reciprocating mechanism for feeding said strips consecutively to and through said printing means, a one revolution clutch operating all said means and mechanism, and a pedal adapted, when pressed downward, to disable said strip feeding mechanism while continuing said clutch in mesh,—whereby a plurality of printing operations may be performed with the particular strip then in printing position, the combination, with said apparatus, of an automatic device holding said pedal, when depressed, in such depressed position until the latter portion of the current clutch revolution, whereby said strip feeding mechanism is held in disabled

condition until nearly the end of any clutch revolution even though the operator may have released said pedal at an early period in said revolution.

45. The combination, with a power-driven mechanism, of a power disconnecting device normally tending to go into action, a pedal detachably connected to said power disconnecting device and adapted to hold the latter out of action when and while said pedal is depressed, and automatic means adapted when energized to break said detachable connection, whereby said power disconnecting device may be automatically permitted to go into action while said pedal is still in depressed condition.

46. A combination such as defined in claim 45 in which said detachable connection between said pedal and said power disconnecting device comprises a movable element operatively connected to the latter and a swinging link pivoted to the pedal and adapted to engage said movable element only when swung toward it.

47. A combination such as defined in claim 45 in which said detachable connection between said pedal and said power disconnecting device comprises a movable element operatively connected to the latter and a swinging link pivoted to the pedal and adapted to engage said movable element only when swung toward it and in which said automatic means for breaking said connection comprises an electric magnet and movable armature therefor connected to said swinging link.

48. In a power-driven machine adapted to be controlled by a pedal, the combination of a main supporting frame, a power-disconnecting device located in the upper portion of said frame, a pedal pivoted at the rear of said frame and extending toward the front thereof, a lever pivoted at the front of said frame and extending toward the rear thereof, a connection from said lever to said power disconnecting device, and a second connection from said lever to a point on said pedal between its pivot and its free end, whereby the free end of said pedal is set back from the front portion of the main frame and the operator can sit close to the front of the frame when placing his foot on said pedal.

49. A structure such as defined in claim 48 combined with automatic means for breaking said pedal connection, whereby said power disconnecting device can be freed while said pedal is still held in depressed position.

50. In a selective device for use on addressing machines employing address bearing strips fed therethrough by an intermittently acting mechanism and adapted to cooperate with a plurality of selector fingers mounted on fixed pivots, continuously

pressed down toward said strips, and adapted to rest upon said strips if permitted to drop far enough, the combination, with the above recited apparatus, of means holding all said fingers out of contact with said strips whenever the latter are in motion but permitting them to rest on said strips when they are not in motion.

51. In a selective device for use on an addressing machine employing a plurality of stencil cards fed successively along guides to an inking mechanism by a reciprocating claw, the combination, with the above recited feeding and inking mechanism, of a plurality of selective fingers mounted on fixed pivots, continually pressed downward toward said cards and adapted to rest upon them when dropped far enough, and means operated by said inking mechanism permitting said fingers to come in contact with said cards only when the latter are at rest, whereby any dragging of said fingers over said cards is prevented.

52. In an addressing machine the combination of inking mechanism, card guides leading thereto, a series of notched stencil cards, a reciprocating claw adapted to feed said cards along said guides to said inking mechanism leaving each card exposed temporarily in a condition of rest in said guides before it reaches printing position, a finger mounted on a fixed pivot over said guides and adapted to swing into the notch in any card in such position of rest with which it may register, and means normally holding said finger above the plane of the upper surfaces of the cards in said guides but actuated by said inking mechanism to drop it into a card notch only when and while the card is in said position of rest, whereby any dragging of such finger along the upper surface of a card is prevented.
